UNITED STATES PATENT OFFICE.

EDWIN O. WARE, OF SALEM, OHIO.

DESIGN FOR A RIVETING-PRESS FRAME.

SPECIFICATION forming part of Design No. 28,216, dated January 25, 1898.

Application filed August 18, 1897. Serial No. 648,725. Term of patent 14 years.

To all whom it may concern:

Be it known that I, EDWIN O. WARE, a citizen of the United States, residing at Salem, in the county of Columbiana and State of Ohio, have invented a certain new and useful Design for a Riveting-Press Frame, of which the following is a specification, reference being had therein to the accompanying drawings.

In the drawings, Figure 1 represents a perspective view of my invention; and Fig. 2 is a longitudinal section thereof, disclosing the interior form.

As shown in the drawings, the material or leading feature of my design for riveting-press frames lies in the flat body portion 1 and its projecting gooseneck 2, with lateral flange 3. At the end of the said neck is a cylindrical boss 4, with a threaded vertical opening 5. The body 1 continues to a boss 6, located beneath the boss 4 and also having the vertical opening 7. In Fig. 2 is shown the form of the interior of the body 1, there be-

ing a rectangular chamber 8 with extending wing 9 and channel 10 upon the upper face of the tail 11 of the body 1. At the end of 25 the tail 11 is a countersunk hole 12. In the body 1 are the holes 13, disposed oppositely to each other. At the front of the body 1 are also disposed the oppositely-projecting lugs 14, in which are the open slots 15. 30

Having thus described the form of my design, showing both the exterior and interior contour, the said form being such that both are largely visible and both contribute to the utility of the invention, what I desire to secure by my Letters Patent and claim is—

The design for a riveting-press frame as herein shown and described.

In testimony whereof I affix my signature in presence of two witnesses.

EDWIN O. WARE.
